[57] CLAIM

The ornamental design for a trumpet, as shown and described.

DESCRIPTION

FIG. 1 is a side elevational view of a trumpet showing my new design;

FIG. 2 is a perspective view of a trumpet as shown in FIG. 1; and,

FIG. 3 is a perspective view of the trumpet from the opposite side of that shown in FIG. 2.

The broken lines shown in all views are for illustrative purposes only and form no part of the claimed design.
